[57] CLAIM

The ornamental design for an article of furniture, as shown and described.

DESCRIPTION

FIG. 1 is an isometric view of an article of furniture, taken from the front, right, upper corner of the article, showing my new design embodied in a sofa, with an isometric view of the sofa taken from the front left upper corner of the sofa being a mirror image thereof;

FIG. 2 is an isometric view of a second embodiment of an article of furniture, taken from the front, right, upper corner of the article, showing my new design embodied in a love seat, with an isometric view of the love seat taken from the front left upper corner of the love seat being a mirror image thereof; and,

FIG. 3 is an isometric view of a third embodiment of an article of furniture, taken from the front, right, upper corner of the article, showing my new design embodied in an armchair, with an isometric view of the armchair taken from the front left upper corner of the armchair being a mirror image thereof.

The portions of the article of furniture which have not been shown or described with respect to the drawings from no part of the claimed design.
